(57) **CLAIM**

The ornamental design for a peanut shaped container, as shown and described.

DESCRIPTION

FIG. 1 is a perspective view of the peanut shaped container shown disassembled;

FIG. 2 is a cross sectional view of the peanut shaped container shown disassembled;

FIG. 3 is a cross sectional view of the peanut shaped container shown assembled;

FIG. 4 is a front elevaton view of the peanut shaped container shown in use; and,

FIG. 5 is a front elevation view of the peanut shaped container shown in use.

The broken line showing of environment in FIGS. 4 and 5 is for illustrative purposes only and forms no part of the claimed design.
